UNITED STATES PATENT OFFICE.

KURT LEHMANN, OF NEW YORK, N. Y., ASSIGNOR TO SO-ME-ON CORPORATION, OF NEW YORK, N. Y., A CORPORATION OF NEW YORK.

DESIGN FOR AN APPLIQUÉ MOTIF.

Application filed February 18, 1926. Serial No. 16,565. Term of patent 3½ years.

To all whom it may concern:

Be it known that I, KURT LEHMANN, a citizen of the United States, residing at New York city, county and State of New York, have invented a new, original, and ornamental Design for an Appliqué Motif, of which the following is a specification, reference being had to the accompanying drawing, forming part thereof.

The figure is a plan view of an appliqué motif showing my new design.

I claim as my invention:

The ornamental design for an appliqué motif substantially as shown.

KURT LEHMANN.
